CURRENT CONTROLLING APPARATUS

Hugh E. Young, Chicago, Ill.

Application March 1, 1933, Serial No. 659,180

3 Claims. (Cl. 176—10)

This invention relates to improvements in current controlling apparatus and, more especially, such apparatus embodying a grid-controlled arc rectifying tube.

In my application, Serial No. 618,369, filed June 20, 1932, Patent 2,071,446 of February 23, 1937, I have disclosed the broad idea of maintaining constant current in a load circuit such as a series lamp circuit. By shifting the phase 10 of grid excitation of a pair of rectifying tubes responsive to current flow in the load or work circuit, the effective flow of current per unit of time is maintained constant for all variations of load resistance from maximum for which the 15 circuit is designed to substantially short circuit value. In that system both lobes of the alternating current wave are transmitted through the load circuit. I have discovered that a series lamp circuit need not employ so-called full wave rectification, but will operate satisfactorily with full illumination upon half wave rectification of commercial sixty cycle current, and at a substantial reduction in energy expended for a given amount of illumination. Since the effective 20 current flow per unit of time according to the present invention is made up of impulses of a frequency the same as the frequency of the impressed alternating current, whereas according to the system of said prior application, the impulses are of a frequency double that of the impressed frequency, it is to be observed that the 25 impulses of current flow according to the present invention are of greater amplitude, i. e., higher value of instantaneous current flow. The result is a greater instantaneous heating of the filament in the case of a lamp or greater instantaneous magnetic effect in case of electromagnetic apparatus. This offers definite advantages 30 for certain classes of service.

The invention is capable of many applications. In order to illustrate one, I have shown apparatus for controlling the direct current delivered by the tube, for example, to a series street lighting system, in which the effective current flow 45 per unit of time is automatically maintained substantially constant regardless of variations in the load. In such systems it is customary to provide automatic short circuits (not shown) for the lamps so that as one burns out, it is automatically short circuited. It will be seen, therefore, 50 that the resistance in the line will vary from time to time, depending upon the number of lamps in commission. By the use of my invention, the effective current flow delivered per 55 unit of time will be maintained substantially

constant, regardless of variations of resistance from maximum value for which the system is designed to substantially short circuit value.

In general, it may be stated that an arc rectifying tube is a rectifier, the starting of which can be controlled by a grid. After starting, the grid has no further control over the arc, either to modulate, limit or extinguish it. When the plate voltage is removed, however, the arc will stop. With an A. C. current delivered to the 10 plate, naturally the arc will have to be started for each cycle. The time of starting, therefore, will determine the average current delivered. I have provided means controlled by the load for automatically varying the timing of the potential on the grid so that the average current delivered by the tube will be substantially constant, regardless of variations in the load.

Other features and advantages of my invention will appear more fully as I proceed with my 20 specification.

In those forms of devices embodying the features of my invention shown in the accompanying drawings—

Figure 1 is a diagrammatic view of my improved apparatus; and Figs. 2 and 3 are similar views showing modifications.

In Fig. 1, the A. C. power supply is indicated by 110, 111. 112 indicates the arc rectifying tube with the plate 112^a, grid 112^b and cathode 112^c. 30 This tube, as here shown, delivers impulses of unidirectional current or direct current to the line 128 containing, for example, the street lamps 113 arranged in series.

150 indicates a pliotron tube with the plate 35 150^a, grid 150^b and cathode 150^c. The plate of the tube 150 is connected by the wire 151 to a battery 152, the other terminal of which is connected by the wire 153 to the grid 112^b of the tube 112. The cathode 150^c is connected by the 40 wire 154 to the cathode 112^c of the tube 112. 155 indicates a grid transformer for supplying grid voltages to the grid 150^b of the tube 150 from the line 110, 111. The secondary coil 155^a of the transformer has a mid-tap leading through 45 the wire 156 to the grid 150^b. One terminal of this coil leads through the resistance 157 to the cathode 150^c and the other terminal leads through the inductance 158 to the cathode 150^c.

159 indicates a movable core in the inductance 50 158 connected to the lever 160 pivoted at 161, the other end of which is connected to a movable core 162 in a solenoid 163 connected in series with the line 128.

Variations in the inductance 158 caused by 55

- movements of the core 159 will change the relation between the inductance and resistance in the supply to the grid 150^b which will split the phase of the current delivered to the grid 150^b. Variations in the load in the line 128 will tend to move the core 121, causing the core 159 in the inductance 158 to be shifted to vary this inductance. The battery 152 is arranged to deliver a counter or non-starting voltage on the grid 112^b. The 10 tube 150, however, is adapted to deliver a voltage during each half cycle which is sufficient to overcome the counter voltage of the battery 152 and impose a starting voltage on the grid 112^b. The exact time in each half cycle, however, when 15 the voltage delivered by the tube 150 overcomes the battery voltage is shifted by the extent of the phase splitting. The extent of the phase splitting is varied by variations in the inductance 128 caused by variations in the line load.
- 20 The parts are so arranged and proportioned that variations in the line load will change the inductance 158 to shift the timing of the starting voltages on the grid 112^b to maintain the effective value of current flow per unit of time 25 transmitted through the tube 112 substantially constant.
- Another method for carrying out the invention is illustrated in Fig. 2 where the A. C. line wires are indicated by 210, 211, the line by 228, 30 the lamps by 213, the coil in series with the lamps by 220 and the movable core therein by 221.
- The arc rectifying tube is indicated by 212 and the same is provided with the plate 212^a, grid 212^b and cathode 212^c.
- 35 In the device here shown, the timing of the impulses on the grid 212^b is controlled by the amount of current by-passed. The core or armature 221 is connected by the pivoted lever 222 to the variable condenser 258. 255 indicates a 40 grid transformer, the primary 255^a of which is supplied from the A. C. lines 210, 211. The secondary 255^b supplies the grid 212^b. 260 indicates a variable inductance operated by a movable core 260^b connected to the lever 222.
- 45 In the operation of the device, any increase tendency of current in the line 228 causes the solenoid 220 to rock the lever 222 to move the movable plate 258^a of the variable condenser 258. This will change the capacity of the condenser to advance or retard the starting voltage in the primary 255^a of the grid transformer. In this way, the timing of the starting voltages on the grid 212^b may be shifted with respect to the alternations of potential on the lines 210, 211.
- 55 In the form shown in Fig. 3, the A. C. power lines are indicated by 310, 311, the load line by 328, the lamps by 313, the arc rectifying tube by 312 with the plate 312^a, the grid 312^b and the cathode 312^c.
- 60 352 indicates a battery connected to the grid 312^b and to the line wire 311. In series with this battery is a resistance 360 and variable inductance 358. 320 indicates a solenoid in series with the line 328 containing the movable armature 321 connected by the lever 322 to a movable core 358^a in the variable inductance 358. In this device, the timing is accomplished by varying the inductance in the battery circuit. The parts are so arranged, for example, that any tendency 65 of the current in line 328 to increase will cause the plunger 321 to be pulled in further, which will operate on the plunger 358^a to increase the inductance 358 in proportion to the resistance 360.

This increase of inductance causes a time delay of current to the grid 312^b which is of such proportion as to maintain the current through the tube substantially constant.

It is to be observed that in each of the above 5 described embodiments of my invention the responsive element, such as the direct current solenoid, is actuated by the current flowing in the lamp or load circuit, and this responsive element is capable of immediately and instantly effecting 10 a shift in the grid excitation of the tube which is directly in series with the work circuit, whereby the flow of current may be regulated substantially within the half-cycle. As a result, the effective current flow in the work circuit may be 15 kept constant with a high degree of accuracy and within a remarkably small tolerance or margin.

While I have shown and described certain embodiments of my invention, it is to be understood that it is capable of many modifications. 20 Changes, therefore, in the construction and arrangement may be made without departing from the spirit and scope of the invention as disclosed in the appended claims, in which it is my intention to claim all novelty inherent in my invention as broadly as permissible, in view of the prior art.

What I regard as new, and desire to secure by Letters Patent, is:

1. In combination, an alternating current supply; a grid controlled arc rectifying tube delivering direct current; a source of constant potential applied to the grid of said tube; a second grid controlled arc rectifying tube in the grid circuit of said first mentioned tube; a phase-splitting 35 circuit supplying potential to the grid of said second tube; and means whereby the relation of the constants of the phase-splitting circuit is altered to change the current flow through said second tube to overcome the bias on said first 40 tube to control the direct current output of said tube throughout its full range.

2. A device of the character claimed in claim 1 wherein said means is controlled by the amount of direct current delivered by said first tube. 45

3. In combination, an alternating current supply line, a normally closed direct current work circuit of variable resistance comprising a plurality of series connected incandescent lamps and a grid controlled tube conductively connected 50 in series, said tube having a grid and a plate and being rendered conductive by excitation of its grid to conduct current during half cycles of the same polarity whereby the load circuit is traversed by direct current only, a grid excitation 55 circuit, means energized from said supply line for applying grid potential to said excitation circuit synchronously with the application of alternating potential of one polarity to said plate, a solenoid connected in series in said work circuit 60 having a core movable by current flow through said solenoid, spring means controlling the position of said core to counterbalance the pull thereupon for various positions thereof, and means comprising a variable inductance having a movable core mechanically connected to the core of 65 said solenoid for shifting the phase of grid excitation substantially instantaneously to keep the effective current flow in the work circuit substantially constant throughout all variations in 70 resistance of the work circuit to which it is subjected.

HUGH E. YOUNG.
